DESIGN FOR A GRAVE MARKER

Luther B. Seibert, Greensburg, and Noble Neilan
Williams, Pittsburgh, Pa.

Application April 28, 1936, Serial No. 62,353

Term of patent 14 years

To all whom it may concern:

Be it known that we, Luther B. Seibert and Noble Neilan Williams, citizens of the United States and residents, respectively, of Greensburg, Westmoreland County, and Pittsburgh, Allegheny County, both in the State of Pennsylvania, have invented a new, original, and ornamental Design for Grave Markers, of which the following is a specification, reference being had to the accompanying drawing, forming part thereof, in which:

We claim:

The ornamental design for a grave marker, as shown.

LUTHER B. SEIBERT.
N. NEILAN WILLIAMS.
